UNITED STATES PATENT OFFICE.

WILLIAM FOX, OF STEUBENVILLE, OHIO, ASSIGNOR TO HIMSELF AND
ROBERT J. BEATTY, OF SAME PLACE.

CHUCK FOR HOLDING BOTTLES.

SPECIFICATION forming part of Letters Patent No. 255,384, dated March 21, 1882.

Application filed January 23, 1882. (No model.)

To all whom it may concern:

Be it known that I, WILLIAM FOX, a citizen of the United States, residing at Steubenville, county of Jefferson, State of Ohio, have invented or discovered a new and useful Improvement 5 in Chucks for Holding Glass Bottles; and I do hereby declare the following to be a full, clear, concise, and exact description thereof, reference being had to the accompanying drawings, making a part of this specification, in which—like letters indicating like parts—

Figure 1 is a perspective view of my improved chuck, showing a bottle seated therein with a wire drawn in position for cutting the 15 bottle. Fig. 2 is a longitudinal sectional view of the same. Fig. 3 is a perspective view of a "blown" bottle, as it is technically termed; and Fig. 4 is a similar view of a tumbler made from such bottle.

Heretofore it has been customary to hold 20 glass bottles for cutting by means of a chuck lined or bushed with cork, which was turned and fitted interiorly to receive a bottle of given form and size. Owing to the fact that such bushing is but slightly elastic and covers the 25 whole or greater part of the side wall, it is adapted for use only with the heavier grades of ware; also, in such use it is found impossible to insert all the bottles an equal distance 30 into the chuck. This is due largely to inequalities in shape and size produced in blowing the bottles, which it is practically impossible to avoid. It has consequently been customary to mark with chalk or otherwise the plane for cutting 35 the bottle, which mark served as a guide. Workmen, however, seldom cut to such mark with precision, owing in part to difficulty in holding the wire or cutting device with accuracy. Thus articles intended for a given grade 40 or set seldom agree with each other in height. For the heavier and coarser grades of blown ware such chucks answer a very useful purpose, although their use is attended with inconvenience and difficulties. For light and delicate 45 grades of work they are unsuitable and cannot be used with practical success. For example, if a bottle with very thin light walls be inserted in such chuck sufficiently tight to be held thereby, the walls of the bottle will be bent or com- 50 pressed in places unless a perfect fit is secured within the bushing. This, however, is not

practically attainable, and when such bent or compressed bottle is cut a crack or break is almost inevitable. This is due in part to the unequal pressure, and in part to a tendency in 55 the cutting-wire (the same being pressed upon the bottle with a stick) to catch upon the rim of the article.

The purpose of my invention is to obviate these difficulties in the way of cutting light 60 and delicate ware by means of a chuck that will receive bottles of the usual range of variation in form to a uniform depth and holding the same with uniform pressure upon a comparatively narrow belt or zone; and in so doing 65 I provide better means than heretofore for severing or cutting the bottles with precision. To this end I make use of a chuck, A, which is secured by screw-socket B to a rotary shaft, C, the latter being journaled in any suitable 70 bearings and rotated when in use at high speed by any suitable means.

Within the head of the chuck is made a chamber, a, corresponding approximately to the form of the bottle E to be held therein, but 75 of somewhat greater diameter. To the side wall of this chamber are secured one or more bands, c c', of comparatively thick, soft, and elastic felt, cloth, soft rubber, or equivalent soft and elastic material. These bands may be 80 fastened to the wall by any suitable paste or adhesive material applied with care; but as such paste or adhesive material, when dry, is apt to render the bands less elastic, they should be renewed frequently for delicate work. On 85 account of this difficulty I prefer to make shallow recesses or grooves e in the wall of the chamber, in which the bands c c' are seated. The thickness of the bands should be in excess of the depth of the grooves, so as to afford bearing 90 for the bottle and prevent its sides from touching the metal wall of the chuck.

With small bottles for punch-tumblers and similar articles one elastic band will be sufficient, and it may be placed either at the mouth 95 or farther in toward the base or inner end. I prefer to place it near the base of the bottle, like the band c, Fig. 2, so that it may bear upon the bottle where the glass has more body and strength. With long bottles, however, two 100 bands may be used to advantage, one being near the mouth, as band c', Fig. 2. The length

of chamber a is equal to the full length of the finished article F. A rim or rest, a' , is made at the inner end of the chamber, against which the base of the bottle rests.

Owing to the soft elastic character of the bands e e' and the small surface-contact between them and the bottle, the latter can be inserted the full length of the chamber without causing undue or unequal pressure upon the bottle, notwithstanding the variations in form and size which usually occur in making a given class of ware. Consequently the rim a' of the chuck may be taken as a gage or measure for cutting the bottle, and the preliminary marking heretofore practiced may be dispensed with. In this case the wire w is held by the hand against the rim a' of the chuck and upon the bottle, as illustrated in Fig. 1. By inserting a wire through opening s the article may be removed from the chuck.

By means of my improvement bottles can be cut much more uniformly than by means heretofore employed, there is much less danger of breakage, far more delicate ware can be made, and the work can be done more quickly than heretofore.

I claim herein as my invention—

1. A chuck for holding glass bottles, having on its inner wall one or more bands of felt,

cloth, or equivalent soft elastic material, substantially as and for the purposes set forth.

2. A chuck for holding glass bottles, having in its inner face or chamber wall one or more grooves, e , with a soft, elastic band seated therein, such band or bands having thickness in excess of the depth of groove, substantially as set forth.

3. A chuck, A, for holding glass bottles, having a comparatively narrow band, e , of soft elastic material, secured to its inner chamber-wall near its inner end, substantially as described, whereby the bottle is held by uniform pressure applied near its base.

4. The chuck A, for holding glass bottles, having chamber a therein equal in length to the desired length of finished article, with a rest or stop, a' , at the inner end of such chamber and one or more comparatively narrow bands, e e' , of soft elastic material, secured to the side wall of such chamber, substantially as and for the purposes set forth.

In testimony whereof I have hereunto set my hand.

WILLIAM FOX.
